SEWING CABINET

Patrick Gribben, Woodside, N. Y.

Application November 19, 1953, Serial No. 393,081

6 Claims. (Cl. 223—107)

This invention relates to a sewing cabinet, having the appearance of an ornamentally designed, miniature bureau or chest, and adapted for supporting a substantial number of items of sewing equipment, in a manner that will permit ready access to any of said items, as the need for the same arises.

An important object of the invention is to provide a sewing cabinet which will combine features of utility and ornamental design in an attractive manner.

Another object is to provide a sewing cabinet as stated which will include a selected number of spool-supporting pins, some at least of said pins being shiftable between normal, inoperative, inclined positions, and horizontal, operative positions.

Another object of importance is to incorporate, in the adjustable pins, detent means which will prevent removal of a spool while still allowing free rotation of the spool on the pin while the pin is horizontally disposed, said detent means being inoperatively disposed when the pin is inclined but being still adapted, when inoperatively disposed, to grip the spool to hold the same against accidental dislodgment.

Yet another object is to so design the adjustable pins as to cause the spool itself to hold the pin in a horizontal position, movement of the spool longitudinally of the pin being effective to free the pin for automatic movement to an inclined position.

Still another object of importance is to incorporate the above mentioned features in a sewing cabinet while still allowing its manufacture at a minimum of cost, from inexpensive material such as plastic.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a sewing cabinet formed in accordance with the invention.

Fig. 2 is an enlarged sectional view of one of the fixed pins and of a spool supported thereby, taken substantially on line 2—2 of Fig. 1.

Fig. 3 is a sectional view on line 3—3 of Fig. 1, showing one of the adjustable pins.

Fig. 4 is an exploded perspective view, partly broken away, showing one of the adjustable pins.

The reference numeral 10 has been applied generally to a sewing cabinet formed in accordance with the present invention. The sewing cabinet, in the illustrated embodiment, is formed in the design of a chest of drawers or bureau, but can be shaped as some other item of furniture if so desired, and made of plastic or any other material. In any event, in the example shown, the cabinet has a container including end walls 12, a front wall 14, a top wall or ledge 16, and a back wall 18 rising to a

In use, the pin 36 will normally appear as in dotted height greater than the top wall, the back wall being preferably ornamentally configured as shown.

The front wall is formed with a plurality of drawer openings, in which drawers are slidably mounted. In the example shown, the drawers include a pair of end drawers 20 at each end of the front wall, and a middle drawer 22

2

substantially larger than the end drawers. Drawer pulls 24, which can be formed as pegs of diamond-shaped cross-section, are secured to the several drawer fronts. It will be understood that the drawers can hold various items of sewing equipment, such as needles, pins, extra spools, etc., the larger drawer being adapted to hold sewing items of larger size.

Secured to the front face of the back wall, at the ends of the back wall, are pairs of headed pegs 26, the pegs 10 of each pair being spaced closely from one another. One pair of pegs can be used as shown to support against the back wall a darning egg 28, while the other pair can be used for supporting a scissors, such as shown at 30.

Secured fixedly to the back wall, between the pairs of 15 headed pegs, are stationary, inclined pegs 32. These can be arranged in any desired manner, and in the illustrated example, they are arranged in four horizontal rows, the top row having four pegs, the row next to the top having five pegs, and the two lower rows each having four 20 pegs, each of the lower rows having two pegs at each end and a substantial space in the middle. Spools of thread 34 are positioned on the several fixed pegs, so as to be readily accessible when they are to be used.

In the middle spaces of the two lower rows, adjustable 25 pegs 36 are provided. These are formed as shown in Figs. 3 and 4, each being shiftable between a full line, horizontal position shown in Fig. 3 and an inclined, inoperative position shown in dotted lines in the same figure.

30 Each of the pegs 36 includes a base 38 formed as a short, cylindrical member one end of which is fixedly mounted in a horizontally extending opening formed in the back wall. The base 38, at its other end (Fig. 4) is formed with transversely spaced, apertured ears 40 through which a pivot or hinge pin 42 is extendable.

A leaf spring 44 has one end 46 formed with an aperture through which a nail or tack is extendable to anchor said end to the upper surface of the base 38. Intermediate its ends, the leaf spring is offset downwardly, the downwardly offset portion merging into a free end 50 tensioned to exert a continuous, yielding upward pressure against the underside of an elongated arm 52. Arm 52 is formed at its inner end with an apertured tongue 54 receivable between the ears 40, the pin 42 passing through the tongue for hingedly mounting the arm on the base. 45

Intermediate its ends, the arm 52 is formed with a recess 56, shaped complementarily to an angularly shaped spring detent 58. Detent 58 is formed from a leaf spring, and has a short, flat inner end merging into an inclined 50 midlength portion, said midlength portion merging into an upwardly offset, short extension 62 at the free end of the spring. The inner end of the spring is formed with an opening receiving a nail 64 whereby the inner end of the spring may be fixedly anchored to the arm 52 in the inner end of the recess 56.

The detent is so tensioned as to cause the free end thereof to normally spring upwardly out of the recess 56, as shown in Fig. 3. In this position, said free end will engage against the outer end of the spool 34 to hold the spool against movement axially of the arm 52, while still allowing the spool to rotate freely. When the spool is to be removed, or is not to be used further, the free end of the detent is compressible into the recess 60 by one's finger, and this will free the spool for removal. 65 lines in Fig. 3. In this position of the parts, the spool is extended over the detent, thus to cause the detent to exert pressure against the wall of the spool bore to frictionally engage the spool and prevent accidental removal thereof from the peg or pin 36.

70 Further, in this position of the parts, the arm 52 is inclined, since the spool will have been shifted toward

the free end of the arm, away from the hinge, thus allowing the tension of spring 44 to assert itself and thereby cause the arm 52 to automatically swing upwardly to an inclined position.

When it is desired to position the spool horizontally once again, and allow free rotation thereof, one simply grasps the spool and swings it downwardly, after which the spool is shifted longitudinally of the peg toward the back wall. As soon as the spool shifts to a position over the hinge, it will hold the arm 52 horizontal, and at the same time, the detent will spring outwardly to engage the spool against longitudinal motion in an opposite direction.

It will be apparent, it is thought, that the adjustable pegs can be used throughout, with no fixed pegs 32 being employed. This is thought sufficiently obvious as not to require special illustration herein.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent, is:

1. A sewing equipment holder including a container for sewing items, a wall upstanding from the container, and a plurality of pegs projecting laterally from the wall for supporting selected items of sewing equipment, some at least of said pegs being adjustable between horizontal and inclined positions, the adjustable pegs each including a stationary base rigid with the back wall, and an arm hinged to the base, the hinge connection between the arm and base including a spring tensioned to normally bias the arm to an inclined position, said arm including a retaining spring detent being adapted to be releasably held against upward swinging movement by a spool extended over the hinge connection and held in position by said spring detent.

2. A sewing equipment holder including a container for sewing items, a wall upstanding from the container, and a plurality of pegs projecting laterally from the wall for supporting selected items of sewing equipment, some at least of said pegs being adjustable between horizontal and inclined positions, the adjustable pegs each including a stationary base rigid with the back wall, and an arm hinged to the base, the hinge connection between the arm and base including a spring tensioned to normally bias the arm to an inclined position, said arm being adapted to be releasably held against upward swinging movement by a spool extended over the hinge connection, each of said adjustable pegs further including detent means carried by the arm at its forward end and adapted for engaging the forward end of a spool against movement off said hinge connection.

3. A sewing equipment holder including a container for sewing items, a wall upstanding from the container, and a plurality of pegs projecting laterally from the wall for supporting selected items of sewing equipment, some at least of said pegs being adjustable between horizontal and inclined positions, the adjustable pegs each including a stationary base rigid with the back wall, and an arm hinged to the base, the hinge connection between the arm and base including a spring tensioned to normally bias the arm to an inclined position, said arm being adapted to be releasably held against upward swinging movement by a spool extended over the hinge connection, each of said adjustable pegs further including detent means carried by the arm at its forward end and adapted for engaging the forward end of a spool against movement off said hinge connection, said detent means being formed as a leaf spring tensioned to spring outwardly from the arm, to engage against an end wall of the spool.

4. A sewing equipment holder including a container

for sewing items, a wall upstanding from the container, and a plurality of pegs projecting laterally from the wall for supporting selected items of sewing equipment, some at least of said pegs being adjustable between horizontal and inclined positions, the adjustable pegs each including a stationary base rigid with the back wall, and an arm hinged to the base, the hinge connection between the arm and base including a spring tensioned to normally bias the arm to an inclined position, said arm being adapted to be releasably held against upward swinging movement by a spool extended over the hinge connection, each of said adjustable pegs further including detent means carried by the arm at its forward end and adapted for engaging the forward end of a spool against movement off said hinge connection, said detent means being formed as a leaf spring anchored at its rear end to the arm and tensioned at its forward free end to spring outwardly from the arm, to engage against an end wall of the spool.

5. A sewing equipment holder including a container for sewing items, a wall upstanding from the container, and a plurality of pegs projecting laterally from the wall for supporting selected items of sewing equipment, some at least of said pegs being adjustable between horizontal and inclined positions, the adjustable pegs each including a stationary base rigid with the back wall, and an arm hinged to the base, the hinge connection between the arm and base including a spring tensioned to normally bias the arm to an inclined position, said arm being adapted to be releasably held against upward swinging movement by a spool extended over the hinge connection, each of said adjustable pegs further including detent means carried by the arm at its forward end and adapted for engaging the forward end of a spool against movement off said hinge connection, said detent means being formed as a leaf spring tensioned to spring outwardly from the arm, to engage against an end wall of the spool, the leaf spring being anchored at its rear end to the arm, and being formed with a downwardly offset midlength portion, merging into an upwardly offset spool engaging extension, the arm having a recess into which said midlength portion is depressible.

6. A sewing equipment holder including a container for sewing items, a wall upstanding from the container, and a plurality of pegs projecting laterally from the wall for supporting selected items of sewing equipment, some at least of said pegs being adjustable between horizontal and inclined positions, the adjustable pegs each including a stationary base rigid with the back wall, and an arm hinged to the base, the hinge connection between the arm and base including a spring tensioned to normally bias the arm to an inclined position, said arm being adapted to be releasably held against upward swinging movement by a spool extended over the hinge connection, each of said adjustable pegs further including detent means carried by the arm at its forward end and adapted for engaging the forward end of a spool against movement off said hinge connection, said detent means being formed as a leaf spring tensioned to spring outwardly from the arm, to engage against an end wall of the spool, the leaf spring being anchored at one end to the arm, and being formed with a downwardly offset midlength portion, merging into an upwardly offset spool engaging extension on its free end, the arm having a recess into which said midlength portion is depressible, the extension on the free end of the leaf spring being adapted for depression by the finger of a user's hand to permit movement of the spool longitudinally of the arm.
